UNITED STATES PATENT OFFICE.

EDWARD W. STOLER AND HOWARD TREASE, OF MANSFIELD, OHIO.

SANITARY BEDPAN.

1,346,388.

Specification of Letters Patent. Patented July 13, 1920.

Application filed June 26, 1919. Serial No. 306,978.

To all whom it may concern:

Be it known that we, EDWARD W. STOLER and HOWARD TREASE, citizens of the United States of America, residing at Mansfield, in the county of Richland and State of Ohio, have invented certain new and useful Improvements in Sanitary Bedpans, of which the following is a specification, reference being had therein to the accompanying drawings.

Our invention aims to provide a bed pan that may be constructed of metal in contradistinction to porcelain or a vitreous material and thus provide a more durable bed pan which we believe may be manufactured at a low cost, since the metal pan may be formed from sheet metal and afterward enameled or otherwise treated so that it will be non corrodible and may be maintained in a sanitary condition.

Our invention further aims to provide a metallic bed pan with a hinged main cover or lid and an auxiliary cover or lid, which when closed, will afford an air tight receptacle and yet permit of the entire interior of the bed pan being easily reached and maintained in a clean and sanitary condition.

Our invention further aims to provide a metallic bed pan that may have a main lid 30 slidable on the pan, in contradistinction to a hinged lid, but in both instances provision is made for sealing the main lid relative to the pan or receptacle.

Our invention still further aims to provide a light weight bed pan that will be hereinafter described and then claimed and reference will now be had to the drawing, wherein—

Figure 1 is a plan of the bed pan;

Fig. 2 is a longitudinal sectional view of the same taken on the line 2—2 of Fig. 1;

Fig. 3 is a plan of a modified form of bed pan;

Fig. 4 is a longitudinal sectional view of the same, taken on the line 4—4 of Fig. 3, and

Fig. 5 is a detail cross sectional view of a portion of the bed pan taken on the line 5—5 of Fig. 3.

Reference will first be had to Figs. 1 and 2 showing a bed pan comprising a receptacle 1 which is semi-circular in plan, said receptacle having an offset portion 2 communicating with an elbow 3 and said elbow affords a bearing 4 for the inner end of a rotatable valve rod 6, said valve rod extending through

a stuffing box 5, carried by the elbow 3. On the valve rod 6 is a butterfly valve rod 7, and the outer end of said rod has a suitable handle 8 which permits of the valve being 60 operated. It is through the medium of the elbow 3 that the receptacle 1 may be thoroughly flushed and cleansed.

The receptacle 1 and the offset portion 2 thereof have walls that gradually increase in 65 height from the front portion of the receptacle to the rear portion thereof, including the offset portion 2, and the upper edges of these walls are flanged so as to provide an inclined top wall 9 which is disposed at an 70 acute angle relative to the bottom wall of the receptacle 1. The top wall 9 has a front portion 10 which is depressed, as at 11, and said top wall also has a rear portion 12 which is substantially rectangular in plan 75 so that it may overhang the offset portion 2 of the receptacle 1. The overhanging portions of the top wall 9 have depressions 13 similar to the depressions 11 and these depressions are slotted, as at 14 to receive 80 bolts 15 having heads 16 pivotally or hingedly connected to the inner face of a main cover 17 adapted to be clamped on the top wall 9. Winged thumb nuts 18 may be screwed on the bolts 15 to hold the bolts in 85 the slots 14 of the depressions 11 and 13.

The main cover 17 conforms in plan to the shape of the top wall 9 and said main cover has its rear edge suitably hinged, as at 19 to the rear straight edge of the wall 9, so 90 that said main cover may be raised and lowered relative to the receptacle 1.

A compressible packing ring or sealing member 20 is suitably mounted on the inclined top plate 9 adjacent the inner marginal edges of the receptacle 1 and the offset portion 2 thereof, so that when the main cover 20 is closed there is air tight or sealed connections between the receptacle and the main cover.

Centrally of the main cover 17 is an opening 21 surrounded by a flange 22 having its upper edge in a plane at an angle to the main cover 20 so that the upper edges of the flange 22 may merge into the cover 105 20 at the front edge of the opening 21. The flange 22 affords a seat for an auxiliary cover 23 having a knob or suitable handle 24. The auxiliary cover 23 is adapted to snugly engage the flange 22 and establish 110 practically an air tight connection between the covers 20 and 23. The cover 23 permits

of the bed pan being used in the usual manner and after such use the main cover 20 may be thrown back and the interior of the receptacle thoroughly cleansed.

- 5 Reference will now be had to Figs. 3, 4 and 5 showing a slight modification of my invention, wherein the receptacle 25 is substantially rectangular in plan and has an elbow 26 at its rear wall normally closed by 10 a hinged cap 27 retained in a closed position by a conventional form of catch 28.

The walls of the receptacle 25 are rolled and shaped to provide holders 29 for a packing ring or sealing member 30 and these 15 holders, at the side walls of the receptacle 25, afford guides 31 for the inturned side flanges 32 of a main cover 33 said cover being also disposed at an acute angle relative to the bottom of the receptacle 25.

- 20 The front edge of the main cover 33 affords a hand grip 34 to facilitate sliding the main cover on and off of the upper edges of the receptacle 25 and said main cover has an auxiliary cover 35 for the same purpose as 25 the auxiliary cover 23.

The guides 31 may be tapered or wedged shaped so that the main cover 33 may be forcibly mounted on the receptacle, where by the packing member will be compressed 30 to insure a sealing connection.

- From the foregoing it will be observed 35 that we have devised a novel metallic bed pan that may be stamped and pressed from sheet metal and the inner and outer walls of the metal enameled and finished so that the bed pan will have practically the same appearance as a bed pan made of porcelain, china or other vitreous material. Our bed pan will be lighter in weight, easy to handle

with no danger of the same being broken 40 should the pan or parts thereof be accidentally dropped.

While in the drawings we have illustrated the preferred embodiments of our invention, it is to be understood that the structural elements are susceptible to such variations and modifications as fall within the scope of the appended claims.

What we claim is:—

1. A bed pan made of metal and comprising a receptacle having a rear offset portion, said receptacle having an inclined overhanging top wall, an elbow communicating with the rear offset portion of said receptacle, means for closing said elbow, an inclined 55 main cover hinged at the rear edge of the overhanging top wall, said main cover including an auxiliary cover carried by said main cover and disposed at an angle thereto, and means carried by the front edge of 60 said overhanging top wall and by the side edges thereof adjacent the rear edge of said top wall adapted to be swung into engagement with said top wall and fixed relative thereto so as to hold said main cover on 65 said receptacle.

2. A bed pan as characterized in claim 1, wherein said means includes pivoted bolts adapted to enter slots in said overhanging top wall and be fixed by nuts engaging the 70 lower face of said overhanging top wall.

In testimony whereof we affix our signatures in presence of two witnesses.

EDWARD W. STOLER.
HOWARD TREASE.
